ATTORNEY.

UNITED STATES PATENT OFFICE.

WALTER E. WHITE, OF NASHUA, NEW HAMPSHIRE.

EDGE-GRINDING MACHINE.

Application filed May 19, 1925. Serial No. 31,426.

This invention relates to grinding machines and has particular reference to machines for abrasively shaping or finishing the edges of eye-glass lenses, although, as hereinafter explained, other articles can be ground or shaped by machines constructed according to my invention.

When lenses or other articles are subjected to the action of an abrading wheel, it is customary to manually or mechanically effect a relative traversing movement of the wheel or the article being acted upon by the wheel, to avoid wearing a groove or grooves in the periphery of the wheel. And of course it is desirable that such traversing movement shall be just sufficient to cause equal wear the full width of the periphery of the wheel. If the article or articles successively operated upon are always of the same thickness laterally, the amount of traversing movement can always be the same. But if, for instance, only a single lens is to be ground at one time and at another time two or more lenses clamped side by side are to be ground, there must be a change in the amount of the traversing movement if the wear of the periphery of the wheel is to be uniform across its full width.

The principal object of this invention is to provide a grinding machine in which the relative lateral movement of the grinder and the article or articles being operated upon will be automatically reversed when one side or the other of the article or articles reaches one side or the other of the periphery of the grinder, and having means whereby the amount of the traverse may be varied according to the thickness of the article or group of articles relatively to the width of the periphery of the grinder, whereby the wear of the grinder will be uniform from one edge to the other of its periphery, whether the lens or other article or articles be thick or thin.

With the above and other objects as hereinafter referred to in view, the invention consists in the construction and combination of parts substantially as hereinafter described and claimed.

Of the accompanying drawings which illustrate one embodiment of my invention in which a lateral or traversing movement is imparted to a grinding wheel rather than to an article which is to be ground:—

Figure 1 is a plan view of the machine.

Figure 2 is a side elevation of the same.

Figure 3 is a detail view, on a larger scale, partly in section, looking in the direction of the arrows 3 in Figures 1 and 2.

Figure 4 is a detail elevation of some of the elements of the machine which are partly shown by Figure 2.

Similar reference characters indicate similar parts in all of the views.

A suitable water-containing base 12, having a partial cover plate 11, is provided with bearings 13 for the shaft 14 of the grinding wheel 15, said shaft being both rotatably and slidably mounted in said bearings. The shaft and its wheel are rotated at high speed by any suitable motor through a belt engaging a pulley 16 secured to one end of the shaft. The other end of the shaft carries a worm 17 meshing with a worm wheel 18 secured to a shaft 19 mounted in bearings 20 supported by a bracket 21.

The shaft 19 has a worm 22 meshing with a gear or worm wheel 23 which is secured to stud shaft 24 mounted in a bearing 25 projecting from the bracket 21. Mounted on the stud shaft 24, as with a splined connection, so as to be rotated by the shaft but longitudinally adjustable thereof for a purpose explained hereinafter, is an arm 26.

A wheel 27, hereinafter referred to as a cam, is pivotally connected at 28 to one end of the arm 26, and diametrically opposite said pivot the cam carries a screw 29 the inner end of which bears against the other end of the arm 26. By turning the screw 29 the cam can be tilted more or less relatively to a plane perpendicular to the axis of the shaft 24.

The outer face of the cam bears against a roll 30 carried by a lug 31 of an arm 32 pivoted to the base at 33 and having a yoke 34 engaging a grooved collar 35 secured to the outer end of the grinding wheel shaft 14. A spring 36 connecting the arm lug 31 with a suitable fixed point effects return movement of the arm.

It will now be understood that, through the mechanism described including the gearing, the cam 27 revolves slowly and, through the arm 32 and its connections and the spring 36, and the shaft 14, causes the grinding wheel 15 to move laterally first in one direction and then in the other direction, a distance determined by the angle to which the cam 27 has been adjusted by the screw 29.

I will now describe the work support as it is constructed for properly holding and rotating lenses the edges of which are to be ground:—A work-supporting bracket 37 is formed at its lower edge with lugs 38 which receive the inner ends of bearing screws 39 mounted in small lugs or uprights 40 of the plate 11. The upper edge of said bracket is divided to form bearings 41, 42, 43, in alinement. Mounted in said bearings are shafts 44, 45, carrying at their inner or adjacent ends pads or disks 46, 47, to grip the work between them. Details of these shafts will be explained hereinafter.

The desirable slow drive of the shafts 44, 45, is obtained from the shaft 19. To this end the shaft 19 has a bevel pinion 48 meshing with a bevel gear 49 carried by a stud shaft mounted in the adjacent lug 40 and carrying also a pinion 50 which meshes with a pinion 51 carried by one end of a long shaft 52 which extends through to the other side of the pivoted bracket 37. Said pinion 51 transmits motion through a small pinion 53 to the gear 54 of the shaft 44.

The long shaft 52 at its other end has a pinion 55 which transmits motion through a small pinion 56 to the gear 57 of the shaft 45.

The shaft 44 is of suitable construction, as of two parts screwed together, so as to carry a pattern disk 58 of any desired shape, the construction of said shaft being such that pattern disks of different shapes may be substituted one for another. Said shaft requires no longitudinal adjustment. That is, its end disk or work-engaging pad 46 preferably remains always in about the position indicated in Figure 1. The other work-engaging disk 47 however is adjustable by means of its shaft, to enable articles of different thicknesses to be clamped or gripped between the two revolving disks, or to enable either one or a plurality of articles, duplicates as to form, to be so clamped or gripped. To this end the shaft 45 is variable in length, as by making it of a plurality of sections screwed together, one of said sections having a milled disk 59 in the space between the bearings 42, 43, to enable that section to be rotated in order that the shaft 45 as a whole may be increased in length to force its disk 47 toward the disk 46 to clamp the work, or decreased in length to withdraw the disk 47 to release the work.

If the article to be ground is a thin one, the traverse-controlling cam 27 is adjusted to occupy a practically extreme tilted position so that the grinder will be shifted back and forth laterally to an extent substantially equaling the width of its periphery to cause equal wear from side to side. But if the article is a thick one, or if a plurality of articles are clamped side by side between the disks 46, 47, then the cam is adjusted to cause less lateral shifting of the grinder, so

that neither side of the article or group of articles will ever be in a position out of contact with the grinder.

I will now describe the mechanism for causing the edges of the lenses or other articles to bear properly against the grinder to shape the articles, by controlling the swinging movements of the work-carrying bracket 37.

An angular-shaped arm 60, pivoted at 61 to lugs rising from the plate 11, has an upright finger 62 bearing against the pattern disk 58, and is formed with a horizontal threaded extension 63. Fitting the extension 63 is a cone-shaped nut 64 having a knob 65. Mounted in a rigid bridge-piece 66 above the cone nut 64 is an adjustable set screw 67 the lower end of which forms a stop coacting with the inclined upper surface of the cone nut in determining the position of the finger 62 relatively to the axis of rotation of the pattern disk 58.

As indicated in Figures 1 and 2, the shank of the cone nut is provided with scale marks. A pointer 68 projecting from the bridge-piece 66 coacts with said scale marks to indicate various adjustments in the distance of the control finger 62 from the axis of rotation of the pattern disk 58.

When one or more lenses or other articles are gripped or clamped between the rotary disks 46, 47, as indicated by the broken lines in Figure 1, and the machine is in operation, said articles are revolved slowly and their edges bear against the wheel 15 with such pressure as is due to the swinging bracket 37 gravitating toward the said wheel 15. Since the control finger 62 remains stationary in the position to which it has been adjusted by the cone-nut 64 cooperating with the stop-screw 67, the limit of inward swinging movement of the work-carrying bracket 37 is determined by the pattern disk riding against said finger 62. Obviously therefore, if an oval or other shaped disk 58 is substituted for the circular one illustrated, the bracket 37 will swing toward and from the wheel 15 so that the articles will be ground to a shape corresponding with that of the pattern disk. Accuracy in this respect is ensured, due to the pivot 61 of the arm 60 being in alinement with the pivots 39 of the bracket 37, as indicated by comparing Figures 1 and 2. The pattern disk will always contact with the same portion of the face of the finger 62 regardless of wear, thereby ensuring accuracy of the work done.

It is sometimes desirable to true the wheel 15 by moving it laterally in less time than would be required by the speed-reducing worm gearing between the shaft 14 and the cam-carrying stud shaft 24. To provide for this, the arm 26, (see Figure 3) is splined on the stud shaft 24 and is adjustable thereon as by means of a screw 69 passing

through the arm 26 and bearing against the outer face of the wheel 23. Said screw 69 can be quite rapidly operated manually to cause the cam to shift outwardly or back so as to cause the arm 32 to reciprocate the wheel shaft 14 while a tool is being held against the periphery of the wheel 15 to true it. And such screw 69 can be actuated to cause the truing tool to operate not only the full width of the periphery of the wheel 15 but to pass beyond the side edges thereof so as to leave no edge ridges.

I do not limit myself to the operation upon articles which are to be rotated during the grinding thereof. For instance, by interrupting the train of gearing, as by removing the gear 49 or shifting it out of mesh with the pinion 48, the shafts 44, 45, will not be rotated. Then any article can be clamped between the disks 46, 47, and will be ground or sharpened by the wheel 15, the latter still having the same lateral traversing movement as hereinbefore described.

In operation, the shaft 14, carrying the grinding wheel 15, is driven at high speed and its worm 17 causes the cam 27 to rotate slowly, through the medium of the worm wheel 18, shaft 19, worm 22, and the worm wheel 23 which is secured to the stud shaft 24, the latter carrying said cam. The cam, acting on the roll 30 of the lug 31 of the lever arm 32, imparts a slow traversing movement to the grinding wheel shaft. The fact that the worm 17 moves longitudinally with the shaft 14 does not interfere with effective operation of the machine since the only effect of such movement is that when it is moving in one direction the worm wheel 18 is rotated a little faster than would be the case if the worm 17 did not move endwise, and when moving in the return direction the worm wheel 18 is rotated a little faster.

By reference to Figure 2 it will be seen that the lug 31 projects from the arm 32 at a point nearly mid-way of the pivot or fulcrum of said arm and its upper end which has the yoke 34. Therefore the cam need not be very large, nor tilted very far, because the extent of traverse imparted to the grinding wheel is substantially double the amount of motion imparted to the lug 31 by the cam.

Having now described my invention, I claim:

1. A machine of the character described, comprising a grinding wheel and a work holder one of which is laterally movable relatively to the other, and means for variably controlling the amount of said lateral movement, said means including a rotary arm, a circular member pivotally connected to said arm at one side of the center of said member the free end of said member being laterally adjustable relatively thereto, and a lateral-movement-controlling member contacting with one face of said circular member.

2. A grinding machine having an abrading wheel, a workholder, and means including a circular adjustable cam pivotally supported at its periphery for effecting a traversing movement of one relatively to the other.

3. A grinding machine having a slidably mounted power-driven shaft carrying an abrading wheel, a rotary work holder, worm gearing for transmitting motion from said shaft to the work holder, an arm connected to rotate with one of the members of the worm gearing, a cam wheel pivotally connected to said arm at one side of its center, means for holding said cam wheel more or less tilted, and means operated by the outer face of the cam wheel for effecting longitudinal movement of the abrading wheel shaft.

4. A machine of the character described, comprising a grinding wheel, a rotary work holder pivotally mounted to permit the work to gravitate toward the grinding wheel and carrying a pattern disk, a pivoted arm having a finger against which the pattern disk bears, the pivots of said arm and work holder being in axial alinement, and means for adjusting said pivoted arm.

5. A grinding machine having an abrading wheel, a work holder, and means including a circular adjustable cam pivotally supported at its periphery for effecting a traversing movement of one relatively to the other, means being provided for bodily shifting the cam to impart quick traversing movement when desired.

In testimony whereof I have affixed my signature.

WALTER E. WHITE.
